UNITED STATES PATENT OFFICE.

FRANCIS H. TOBIAS, OF NEW YORK, N. Y.

IMPROVEMENT IN MECHANISMS FOR OPERATING SCREW-PROPELLERS.

Specification forming part of Letters Patent No. **145,697**, dated December 16, 1873; application filed October 22, 1873.

To all whom it may concern:

Be it known that I, FRANCIS H. TOBIAS, of New York, in the county of New York and State of New York, have invented certain new and useful Improvements in Propelling Small Boats; and I do hereby declare that the following is a full, clear, and exact description thereof, reference being had to the accompanying drawings and to the letters of reference marked thereon, which form a part of this specification.

This invention relates to a means or mechanism by which a small boat may be propelled by physical power or other means, as desired, having for its object to so combine the parts of the propelling device that one person may propel, reverse, and steer the boat, or more persons may assist in the work, or other power may be applied, if desired; and it consists in the combination and arrangements of the parts, as hereinafter more fully described, and pointed out by the claim.

Referring to the drawing, Figure 1 represents a plan view of a device embodying my invention. Fig. 2 is a side elevation of the same. Fig. 3 represents a portion of the shaft and connecting mechanism; and Fig. 4 is an end view.

When placed in a boat of any ordinary or convenient construction, my invention occupies the position shown in Fig. 2, the boat being represented by dotted lines. A represents the shaft, suitably journaled in the frame H at *a a*, and B is the propeller near the rear end of the shaft, and secured thereto. C C represent two loose pinions upon the shaft, each being provided with a slot on its inner face, corresponding in size to the lugs *b b* on the sleeve D. The shaft A is slotted longitudinally between the pinions C C, and the sleeve D is provided with a feather corresponding in form with and fitting the slot or groove in the shaft A, so that the sleeve may be moved lengthwise upon the shaft between the pinions, and has a positive rotary motion with the shaft. The outside of the sleeve is constructed to receive the forked end of an arm, G, connected with the lever E, by which means the sleeve may be moved back and forth on the shaft A, and connected with either pinion C C, or to occupy a position between the two pinions, thus giving a forward and backward

motion to the propeller, or throwing the same out of gear, as desired. Motion is given to the parts above described through the medium of the cog-wheel I, shaft J, pinion e, and bevel-gear K, all of which is suitably secured by the frame H. The wheel I has the cogs on the lower face, and always remains in gear with the pinions C C, both of which may have a motion independent of the shaft A, unless connected with said shaft by the sleeve D, as before described.

When it is desired to propel the boat by hand or physical power, the cranks *m m* are placed, one upon each end of the shaft L, carrying the gear K, by which means one or more persons may propel the boat; but other power may be applied, if desired.

N represents the rudder, and N' the tiller. It will be observed that the tiller N', lever E, and the cranks M are arranged with such relation to each other that one person may reach them all without moving from his place, and propel, steer, and reverse the propeller, or throw the same out of gear, at will.

By this means a convenient, efficient, and simple propelling device is provided, which may readily be placed in small boats of the ordinary construction, and be operated by one or more persons or other power, as desired.

I do not claim propelling a small boat by physical power, as I am aware this is common; but

Having thus fully described my invention, what I do claim, and desire to secure by Letters Patent, is—

The combination of the propelling mechanism, consisting of propeller, shaft, and pinions, and the operating parts I J e K, the reversing and steering mechanism, the combination and arrangement being adapted for operation as herein shown and described, whereby a boat may be propelled, steered, and reversed by a single person, or steered and reversed by a single person, when propelled by other power, as and for the purpose specified.

In testimony that I claim the foregoing as my own I affix my signature in presence of two witnesses.

FRANCIS H. TOBIAS.
